UNITED STATES PATENT OFFICE.

MARTIN E. BULLWINKEL, OF BROOKLYN, NEW YORK.

TELEPHONE ATTACHMENT.

Application filed April 1, 1925. Serial No. 19,767.

To all whom it may concern:

Be it known that I, MARTIN E. BULLWINKEL, a citizen of the United States, residing in the borough of Brooklyn, county 5 of Kings, city and State of New York, have invented an Improvement in a Telephone Attachment, of which the following is a specification.

Inasmuch as a general rule, telephone instruments, particularly publicly used telephone instruments, are given little care and attention; they become uncleanly, and often times are sufficiently so that they may be the cause of infection by spreading the 15 germs of tuberculosis, and possibly other diseases. For this reason also, it is often found to be practically impossible for persons accustomed to the use of cleanly instruments to utilize public telephones, irrespective of how convenient they may be, and how important at any particular time it is to send a message or hold a conversation over the telephone lines.

The object of my present invention is the 25 provision of a small and inexpensive attachment which may be readily available, easily applied to a telephone instrument, and by the use of which the liability of becoming infected by any disease germs which 30 may be lurking in an unclean telephone is substantially eliminated, and also in the use of which the transmission of the message over the telephone is not interferred with to any perceptible extent. To this end in 35 carrying out my invention I employ a blank made of suitable material and shaped to any desired configuration, and which may be readily taken from a dispenser adapted to contain the same and placed adjacent the 40 telephone instrument, or which may be carried by the user, and which may be easily placed in position on the transmitter mouth piece, so as to be supported thereby, and so as to overhang the opening therein. It 45 will be understood however, that while the invention is particularly adapted for this purpose its use is not so limited, as it may be employed for other and equally obvious 50 purposes without departing from the nature and spirit of the invention.

The telephone attachment made in accordance with my invention will be hereinafter more particularly described in conjunction with the accompanying drawings, of which, 55 Fig. 1 is a side elevation of a telephone

transmitter with my improved attachment applied thereto.

Fig. 2 is a perspective view of the attachment, and

Fig. 3 is a plan on an enlarged scale of 60 the blank from which the attachment is made.

Referring to the drawing the telephone attachment made in accordance with my invention may be constructed from a blank of 65 paper or other material having sufficient body and strength to serve the intended purposes. This blank comprises a long flap 10, and a short flap 11 in which there is an opening 12, the extent of the flaps being determined by a transverse fold line 13, on 70 which the body of the blank is folded to form the flaps. Also as clearly indicated in Fig. 3 of the drawing the blank may be folded or creased along a central longitudinal line 14, in order to more readily apply 75 the attachment to the telephone for use.

In the drawing the mouth piece of a telephone transmitter is indicated at 15, and the body of the transmitter at 16.

In using the attachment the same may be placed in a container adjacent a telephone instrument, so as to be readily available in the same manner, for example, as various forms of paper drinking cups are retained in containers adjacent a water cooler, or a number of these telephone attachments may readily be carried in the pocket of a coat or vest so as to be readily available for use when desired. In applying the attachment 90 the base or lower end of the long flap is clasped by the fingers, and by virtue of the transverse fold line the short flap may be turned outwardly along the transverse fold line 13, so that this short flap may be caused 95 to engage the mouth piece of the transmitter by passing the mouth piece through the opening 12, and then permitting the mouth piece to support the attachment, in which position as will be understood the long flap 100 covers the opening in the mouth piece of the transmitter, preferably in a position slightly spaced therefrom, as clearly indicated in Fig. 1 of the drawing. With the attachment thus in position the liability of the 105 transmission of disease germs of any kind from the transmitter of the telephone to the mouth of the speaker is obviated, or certainly minimized to a negligible extent.

Furthermore, and as heretofore intimated 110

the use of this attachment does not in any way materially interfere with the transmission of the speech over the telephone.

It will furthermore be understood that the particular form of the attachment as herein shown and described is more or less illustrative, as other and equally obvious forms of the invention, and various materials from which the blank may be made 10 may be employed in carrying out the invention.

It will be equally obvious that the particular use to which the invention is applicable as hereinbefore described is not the only one 15 to which it may be applied, as the attachment may be employed for other similar and obvious purposes.

I claim as my invention:

A telephone attachment comprising a rectangular blank folded transversely to comprise a short flap, and a long flap adapted when folded to lie against each other, there being an opening provided in the short flap for receiving the mouthpiece of a telephone instrument, and there being a crease extending longitudinally in the long flap and into the short flap between the transverse fold in the blank and the opening in the short flap to enable the user to readily separate the flaps and thus facilitate the placing of the attachment on the mouthpiece of the telephone. 20 25

Signed by me this 25th day of Mch., 1925.
MARTIN E. BULLWINKEL.
